Furnace Corporation, Buffalo, N. Y., a corpo-
ration of New York

Application June 23, 1932, Serial No. 618,844

5 Claims. (Cl. 201—75)

Our invention relates to electrical resistors, and has for its general objects the production of a new and improved resistor and a method of making such resistor. More particularly the 5 invention has for its object the production of an improved resistor preferably of the zig-zag type and having conducting terminals of novel construction, made in the form of a self-contained unit of comparatively small size which 10 may be readily introduced into a seat or slot in an electrical furnace and removed therefrom without dismantling or otherwise disturbing the furnace structure.

It has been usual heretofore to emplace resistors of this general type in a chamber built into the electrical furnace with the resulting disadvantage that when replacements were required the furnace had to be partially dismantled or torn down in order to remove the resistor, necessitating shut-downs in the plant while replacements were being made. Furthermore, it has been difficult in prior constructions adequately to protect the terminals against oxidation generally and particularly at their outer ends. Our present invention overcomes these defects by providing a unit resistor readily replaceable and having suitably protected air-cooled terminals, doing away with the need of water-cooling.

To the above and other ends which will subsequently appear our invention consists in the features and methods of construction, combinations of devices and arrangements of parts hereinafter described and particularly pointed out in the appended claims.

The preferred form of the invention is shown 35 in the accompanying drawing wherein

Fig. 1 is a side elevation, partly broken away, of an electrical resistor embodying the invention;

Fig. 2 is a transverse vertical section taken 40 on the line 2—2 in Fig. 1, and

Fig. 3 is an enlarged sectional view of a modified form of terminal.

As shown in the drawing, the unit heating or resistor element designated as a whole by the unit 10 comprises a rectangular box or container 11 open at its top or one side. The box-like sheath or container may be made of any suitable refractory material that is a good conductor of heat, such as recrystallized silicon carbide 45 or bonded silicon carbide. The container provides a housing for a resistor element proper 12, rectangular in form, composed of graphite and preferably of the zig-zag type. The resistor element 12 is of smaller dimensions than the container 11 so as to permit a packing indicated at 13 to be introduced into the container completely covering the resistor 12 on all sides. This packing preferably is a mixture of fire sand or granular silicon carbide, powdered coke and a comparatively small quantity of borax or other fusible material. The packing 13 covers the resistor and fills the container up to within a short distance of its top, the remainder of the space above the packing being filled with a cementitious compound indicated at 14, which is made of any 10 suitable refractory material which hardens when heated, such as silicon carbide and a binder. This cement covering 14 serves not only to provide a gas-tight covering for the open top of the container but also acts to support the conducting terminals, the ends of which are embedded in it so that when the cement hardens the terminals are held rigidly in place.

The terminals, indicated generally at 15, are of a novel construction, each comprising a graphite or carbon rod 16 enclosed in a sheath, jacket or tube 17 of porcelain, sillimanite or other refractory material, and air-tight up to at least 3000° F. The tube extends downward through the cement 14 and into the packing 13, being 20 supported and held rigidly in place by the cement. The space between the rod and the tube is packed with an embedding material indicated at 18 which preferably is a refractory and carbonaceous mixture such as silicon carbide fines and 30 powdered coke or graphite. This mixture minimizes the circulation of gases and insures a reducing atmosphere, the silicon carbide powder being a good conductor of heat, and is effective in cooling the larger end portion of the rod 16. 35 At the top the tube 17 is cemented as indicated at 19 into a counter-sink 20 in a metallic gland 21. This gland is made of a metal that is non-corrosive and a good conductor of electricity, such as Monel metal or nickel, so that a good electrical connection can be made with it by means of a plate or link 22 which is clamped against its top by a nut 23, said nut being screwed onto the upper reduced threaded end portion 21a of the gland or cap 21.

The upper end of the terminal rod 16 is seated in a depression in the end of the gland 21. The lower end portion of the rod is preferably reduced in diameter as indicated at 16a and suitably contacts with the resistor 12. As a result of this 50 construction, with the same current flowing in the circuit more heat will be generated in the portion 16a than in the resistor 12, making it impossible for heat to be conducted away from the resistor through the larger upper portion of 55

the rod 16. This larger portion is of such cross section that little heat is generated in it due to the passage of the electric current, so that it emerges from the furnace at a comparatively low 5 temperature. The steep temperature gradient, or critical point, is confined to the point where the abrupt change in cross section of the rod occurs, namely at the shoulder between the small and large portions. The upper or large portion of 10 the rod is covered by its refractory sheath which extends outward to the cooler point and inward or oppositely to the hotter point of smaller cross-section. At its outer end the tube or sleeve 17 makes an air-tight joint with the metallic gland 15 21, due to the cement 19, and at its inner or hot end the sleeve extends into the packing 13. Due to this construction the necessity for water-cooling 20 of the terminals is avoided, the metallic glands being non-corrosive and having a high melting point, and the large diameter of the terminal rods causing them to generate a comparatively small amount of heat.

The heating unit 10 is made in as small dimensions as may be without sacrificing mechanical 25 strength, and as will be seen is of a suitable shape to enable it to be slipped into a seat or bed 24 in the wall 25 of the furnace. Although particularly adapted for ready replacement, it may 30 of course if found desirable, be built into the furnace.

It will be noted that all of the parts comprised 35 in our improved heating element or resistor device will withstand high temperatures. The metallic gland has a high melting point, does not corrode at high temperatures, and is not affected by carbon at high temperatures, so that no oxide is formed nor is the composition of the metal changed, with the result that even at a very high temperature a good electrical connection is maintained. The porcelain tubes are very refractory 40 and are air-tight up to 3000° F. or more, and are connected to the glands by a refractory joint. The terminal rods are themselves infusible and packed with a high refractory powder. As a result of the arrangement and construction, the 45 entire unit will withstand extremely high temperatures.

Changes may be made without departing from the invention, and as an example we have illustrated in Fig. 3 a modified form of terminal 50 wherein the graphite rod 26 (corresponding to the rod 16 of the Figs. 1-2 construction) is made of two parts 27 and 28, the part 28 of small diameter threading into a tapped seat in the bottom of the larger part 27. This larger part at its upper end projects through an opening in the top of the gland 29 and is threaded as indicated at 30 to receive a block 31 of carbonaceous material with which electrical connection is directly made. The threaded portion 30 of the rod 60 extends downward through the opening in the gland 29 which is screwed on it.

We claim:

1. An electrical resistor provided with a terminal comprising a carbonaceous rod, a refractory tube of porcelain enclosing the rod and air-tight up to at least 3000° F., a non-corrosive metallic gland of metal of high melting point into which one end of the tube is cemented to make a gas-tight joint, a refractory packing of silicon carbide fines or the like between the rod and the tube, and means providing a gas-tight joint between said resistor and the other end of the tube. 10 5

2. A heating element comprising a zig-zag resistor member of carbonaceous material, an open top receptacle of silicon carbide or like refractory material in which said member is housed, a packing between said receptacle and said member in 15 which said member is embedded, said packing comprising a mixture of fire sand, powdered coke and a fusible material, a cementitious covering providing a gas-tight seal over the open top of the receptacle, and conducting terminals embedded 20 at their ends in said packing material and projecting outward from said resistor member, said terminals comprising tubular sheaths, and means providing gas-tight seals at the outer ends of said tubular sheaths. 25

3. A heating element comprising a zig-zag resistor member of carbonaceous material, an open-top receptacle of silicon carbide or like refractory material in which said member is housed, a packing between said receptacle and said member in 30 which said member is embedded, said packing comprising a mixture of fire sand, powdered coke and a fusible material, a cementitious covering providing a gas-tight seal over the open top of the receptacle, and conducting terminals comprising 35 carbonaceous rods and enclosing refractory tubes, the ends of said tubes being embedded in said packing. 35

4. A heating element comprising a carbonaceous resistance member, a container therefor of 40 refractory material, said container having an open top, conducting terminals comprising carbonaceous rods, refractory tubes enclosing said rods, metallic glands into which the outer ends of said tubes are cemented, and a refractory packing completely covering said resistance member, and a cementitious covering providing a top for 45 said container, the end portions of said tubes being embedded in said covering. 45

5. A heating element comprising a carbonaceous resistance member, a container therefor of refractory material, said container having an open top, conducting terminals comprising carbonaceous rods, refractory tubes enclosing said rods, metallic glands into which the outer ends of said tubes are cemented, and a refractory packing completely covering said resistance member and a refractory cover providing a top for said container, the end portions of said tubes being 55 cemented in said cover. 60
